FACSIMILE SYSTEM

William G. H. Finch, New York, N. Y.

Application November 11, 1935, Serial No. 49,222

7 Claims. (Cl. 178—5)

My invention relates to novel apparatus for and methods of transmitting and reproducing pictures or the like.

In the transmission of shaded pictures, a beam of light is caused to scan the picture and then impinge upon a photo-sensitive cell, the intensity of the impinging beam varying in accordance with the shading of the picture. A chopper wheel placed in the path of the light beam to interrupt it at a uniform rate, or equivalent methods are used so that alternating current rather than direct current amplifiers may be employed. The amplified impulses modulate a carrier wave for radio broadcasting thereof. The broadcast signal is accordingly modulated at a fixed frequency at varying amplitude. A radio receiver detects the modulation of the radiated signals to actuate a suitable picture recording element. In order to reproduce the original shaded figure, the detected signals must faithfully represent the original amplitude modulated signals. Vagaries of radio broadcasting transmission, particularly fading, distort the received signals to destroy the relative amplitudes of the actuating recording impulses 25 in the reproduction of the shaded figure being transmitted.

I have invented novel apparatus for converting the varying light intensities of the beam which impinges upon the photo-electric cell to signals having a constant amplitude but of frequency varying in accordance with the intensity of the impinging beam. These signals may be transmitted directly over a wire line circuit or may be used to modulate a radio frequency carrier wave for radio transmission. An ordinary radio receiver is used to detect these constant amplitude signals of varying frequency, and made to actuate well known recording means, or to operate the simple, novel, efficient reproducing units which also form part of my present invention. The reproduced picture is built up by a plurality of short marking impulses. These impulses compose a figure which is shaded in accordance with the transmitted picture. The higher the frequency of the actuating signal, the greater will be the number of marking impulses in a given time, and a darker picture element is recorded.

Pictures reproduced according to my invention are composed of a multiplicity of individual impulses or dots, and may therefore be directly used as half-tone reproductions such as for newspaper printing. My invention is directly applicable for actuating an engraver for directly cutting a zinc plate which may be used in printing presses and

the like for picture printing. Half-tone processes are generally used for breaking up an original photograph into elemental units to avoid ink blurs and to permit finer detail in the printing of pictures. My present facsimile system transmits and reproduces pictures composed of individual impulses. The reproduced picture, having any predetermined detail, may in turn, be directly used for picture printing in newspaper work, or for local perception of the transmitted visual messages or pictures.

Another important feature of my invention is to employ any system of facsimile transmission where the shading of the picture is caused to vary the amplitude of the facsimile signal being transmitted, receive and detect these signals at a distance, and convert them to impulses of constant intensity but of frequency varying in accordance with the original shading of the picture being transmitted. An important resultant advantage is that the major portion of the energy for the printing impulses is generated locally at the receiving station, and the detected signals are used to merely vary the frequency of the said local impulses. I thus provide a simple, rugged, efficient and cheap facsimile reproducing mechanism. The novel reproducing units according to my invention, are useful where direct actuation for half-tone reproduction is desired whereby the picture is built up of discrete impulses, as hereinabove explained. Such a rugged system, which is light in weight, is also particularly useful for aircraft facsimile receivers.

For many applications, it is only necessary to transmit figures which may be built up by merely black and white impulses as, for example, printed or written matter, sketches, unshaded drawings and the like. I provide novel, simple methods for reproducing such black and white pictures wherein the major energy of the marking impulses is locally produced.

Accordingly, it is an object of my invention to provide novel methods for transmitting facsimile signals.

Another object of my invention is to provide novel methods for transmitting facsimile signals of constant amplitude but of frequency varying in accordance with the shading of the picture being transmitted.

It is still another object of my invention to provide novel apparatus for converting varying light intensities to signals of constant amplitude but varying frequency.

A further object of my invention is to provide a novel method for reproducing a transmitted pic-

ture as a series of marking impulses of varying spacing.

Still a further object of my invention is to provide a novel method for converting amplitude modulated facsimile signals to signals having constant amplitude of varying frequencies.

Another object of my invention is to provide novel methods for producing facsimile marking impulses locally and controlling the frequency of said impulses in accordance with received facsimile signals.

A further object of my invention is to provide novel facsimile reproducing apparatus that is simple, rugged, efficient and cheap.

15 There are other objects of my invention, together with the foregoing, which will appear in the detailed description to follow in connection with the drawings, in which:

Figure 1 is one modification of a facsimile transmitting system according to my invention.

20 Figures 2 and 2a are further modifications for a facsimile transmitting system according to my invention.

Figure 3 is a facsimile receiving system for use 25 with the transmitters of Figures 1 and 2.

Figure 4 is a schematic illustration of a well-known facsimile transmitting system which may be used for the following several modifications of facsimile receiving systems according to my invention.

Figure 5 illustrates one modification of a facsimile reproducing system according to my invention.

Figure 6 schematically illustrates a modification 35 of the reproducing unit of Figure 5.

Figure 7 is a sectional elevation of a preferred embodiment of a reproducing unit illustrated in Figure 6.

Figure 8 is another modification of a facsimile 40 reproducing system according to my invention.

Figures 9 and 10 are further modifications of facsimile reproducing systems for black and white pictures or messages.

Referring to Figure 1, I have schematically indicated a method used for varying the intensity 45 of light impinging upon the photo-electric cell 1 in accordance with the shading of a picture 2 mounted on a drum 3. Light from a source 4 is concentrated to a point which is directed along the picture 2 in a predetermined manner. Light is reflected from the surface in varying intensity according to the shading of the picture being scanned. Thus, as a white portion of the picture is passed over, a maximum of light is reflected and made to impinge upon the photo-sensitive surface of the photo-electric cell 1 along the reflected beam 5 in a well-known manner. When a darker portion of the picture is traversed, correspondingly less light is reflected 55 to the photo-sensitive cell 1. The light intensity of the reflected beam 5 is accordingly varied in proportion to the shading of the spot on the picture 2 which the light from the source 4 is scanning. Other methods of scanning a picture for transmission may equally well be used. For example, the light source 4 may be mounted within the drum 5, the picture 2 be translucent, and light is transmitted through it of intensity varying with the shading on it.

70 When a drum is used, the length of the picture is limited. There are several methods and systems where the pictures or messages to be transmitted are on a long sheet which is continuously advanced through the scanning mech-

anism, which may, of course, also be used with my present invention. Such a system is disclosed in my Reissue Patent No. 19,575 of May 21, 1935. The light beam 5 of varying intensity produces fluctuations in the current passing through the photo-electric cell 1 which is connected to the direct current amplifier 6 of the push-pull type. The output 7 of the amplifier 6 is connected to the solenoid 8 which acts upon plunger 9. The push-pull direct current amplifier 6 is 10 preferably of the type disclosed in my co-pending application Serial No. 49,221, filed Nov. 11, 1935. The output stage of the direct current amplifier 6 is arranged to fully energize coil 8b of the solenoid 8 when no signal appears at the input to the 15 amplifier 6, and corresponds to a black segment being scanned on picture 2. When a signal is introduced to the amplifier 6, coil 8a is proportionately energized, while the current through coil 8b is correspondingly decreased. The plunger 9 is 20 thereby attracted up towards coil 8a. The circuits are designed to cause the plunger 9 to be in its lowest position when a black picture segment is scanned; to be attracted to its highest position in the solenoid 8 when a white segment is 25 scanned; and to assume intermediate positions in accordance with the shading of the picture segments.

The plunger 9 is made of soft iron and is preferably laminated to reduce hysteresis and eddy 30 current losses. I have illustrated a spring 10 pressing against a transverse pin 11 fastened at the end of the plunger 9, for mechanically biasing the plunger and steadyng its movements. A metallic projection 14 of the plunger 9 passes 35 through the portion 12 of the insulation structure 13. A contact point 15 is formed at the end of the projection 14. An electro-magnet 16 is arranged to attract an armature 17 when current passes through it. The armature 17 is connected 40 to a flexible spring 18 which is fixedly mounted in the post 19. A contact spring 20 attached to the top face of the armature 17 as shown, coacts with the contact 15.

The local electro-mechanical circuit 30, comprises a battery or direct current source 21, connection 22 to the electro-magnet 16, lead 23 to the metallic post 19 and metal spring 18, metallic armature 17, contact spring 20, contact point 15, lead 24 flexibly connecting projection 14 (and 50 contact 15) to rheostat 25, and lead 26 to primary 27 of transformer 28 and lead 29 to battery 21. When the contact point 15 touches the contact spring 20, it closes the local electrical circuit 30 and current flows through the electro-magnet 16 55 causing it to attract the armature 17, in turn breaking the electrical contact between spring 20 and point 15 when the electro-magnet 16 releases its attraction for the armature 17 which returns to cause re-contacting of point 15 and spring 20 60 to repeat the cycle.

The frequency of vibration of the armature 17 depends primarily on its mass, the elasticity of spring 18 and the distance it must travel in order to re-contact with the point 15. The rheostat 25 65 is used to control the operating current flowing in this local circuit. As the circuit is completed by the contact point 15 and contact spring 20, an electrical impulse passes through the local circuit 30 and is transmitted by the primary 27 70 of the transformer 28 to its secondary winding 31. As contact point 15 is raised, the frequency of vibration of the armature 17 is reduced since the armature 17 has a greater amplitude of vibration and takes more time per vibration. The 75

frequency of interruption of the local circuit 30 is accordingly reduced and the impulses transmitted to the secondary 31 of the transformer 28 are of the same frequency. The action of the 5 local electro-mechanical circuit 30 which I have herein disclosed is analogous to the action of an ordinary buzzer, and the variation of the distance of the contact point 15 corresponds to the adjustment of pitch or vibration frequency of said 10 buzzer. However, I employ this simple means for translating facsimile signals of varying amplitudes to impulses of constant amplitudes and varying frequencies in the following manner:

The facsimile signals introduced to the solenoid 8 causes a varying attraction for the plunger 9 within said solenoid 8 as hereinbefore explained. When a strong signal is introduced to amplifier 6, the plunger 9 is moved nearer to the vibrating armature 17. The frequency of vibration of the 20 armature 17 is thereby increased, and the frequency of the impulses induced in the secondary 31 of the transformer 28 is likewise increased. On the other hand, when a weak signal is introduced corresponding to a bright shading of picture 25 segment being transmitted, the plunger 9 moves away from the armature 17 decreasing the frequency of vibration of said armature 17 and causing a lower frequency of impulses to be induced in secondary winding 31.

30 I provide a mechanical stop 13' mounted in member 13 to limit the amplitude of excursion of the armature 17 from the electro-magnet 16 a predetermined amount. An excess of upward attraction for the plunger 9, caused by a white 35 spot being scanned on picture 2, will move the contact point 15 beyond contacting relation with the spring 20 due to the limitation in the excursion of the armature 17 by the stop 13'. No impulses will therefore be transmitted to the secondary 40 31 while white areas of the picture are being transmitted. Intermediate positions of the plunger 9 in the solenoid 8 are due to intermediate shadings of the picture 2 segments which produce corresponding intermediate amplitudes of 45 signal input to the amplifier 6. The contact point 15 will assume intermediate positions and corresponding variations will occur in the frequency of vibration of the armature 17. Darker areas will produce higher frequencies, and lighter areas 50 will produce lower frequencies of impulses induced in the secondary winding 31 of transformer 28.

The amplitude of the induced voltage impulses will be substantially constant but the frequency 55 will vary in accordance with the shading of the picture being transmitted. These impulses are introduced to an amplifier 32 and may be transmitted at a distance in any well-known manner. The output 33 of the amplifier 32 is shown schematically connected to a switch 34 which, when 60 contacting point 35, transmits the signal impulses directly to the transmission line 36. This line may be a telephone line; or the impulses may be introduced to a carrier telephony or telegraph line system. I have schematically indicated a 65 system whereby the amplified impulses according to my invention may be transmitted by radio. Thus, when the switch 34 contacts with point 37, the lead 38 connects the output 33 to the radio frequency amplifier 39 and the facsimile signals 70 modulate the radio frequency carrier wave introduced to the radio frequency amplifier 39 by the radio frequency oscillator 40 by leads 41. The antenna system 42 transmits the resultant modulated carrier as is well known in the radio art.

The modification I have described in connection with Figure 1 is an electro-mechanical vibratory means for translating picture impulses of varying intensities impinging on a photo-sensitive cell which impulses are of substantially constant 5 amplitude but of varying frequency. These impulses may be directly transmitted by line wires or be radiated by ordinary radio methods. The facsimile signals corresponds to the audio-frequency modulation of a radio frequency carrier 10 wave as used in any audio-frequency broadcasting station. No special equipment is required by such stations for the facsimile broadcasting. The impulses which are induced in the transformer secondary winding 31 may be applied to the ordinary speech input circuits of radio broadcasting systems and be transmitted as though they were audio signals. I have herein provided for white areas of transmitted pictures to correspond to zero facsimile signal, that is, no modulation 15 of the carrier wave will then occur. During the black portions of the picture being scanned, the highest (predetermined) frequency of facsimile signal is transmitted according to my invention.

This frequency may, for example, be 4000 cycles 25 or any other predetermined frequency according to the design and the speed of transmission desired. Frequencies of the order of 100 cycles would cause relatively slow impulses and correspond to an area which is practically white when 30 reproduced as hereinafter described.

Figure 2 shows another method whereby I cause facsimile signals of amplitude proportional to the varying intensity of the scanning light beam 5 reflected from the picture 2 to produce corresponding signals of constant intensity but varying frequency. The output of photo-electric cell 1 is connected to amplifier 6, the output 7 of which is connected to solenoid 43. The amplifier 6 and its output connections 7 are the same as 35 described hereinabove in conjunction with Figure 1. The solenoid 43 has two coils, 43a and 43b, connected as are the coils 8a and 8b of Figure 1 to the amplifier 6 output leads 7. A plunger 44 is attracted up into the solenoid 43 in varying 40 degree in accordance with the facsimile signal strength as hereinbefore explained. I show a spring 45 and transverse pin 46 on the plunger 44. An extension 49 of the plunger 44 is suitably linked at 50 to a lever 51. A boss 52 at the end 50 of lever 51 is secured to the variable condenser shaft 53 of a beat frequency oscillator 54, shown schematically.

The variable condenser used to control the frequency of the output of the beat frequency oscillator 54 is purposely shown in perspective to make clear the action of the plunger 44 on it. The variable condenser rotor plates 55 are rotated by the condenser shaft 53 with respect to the stator plates 55'. The tank circuit 56, including the variable condenser, is part of the variable high frequency oscillatory circuit 57. The tank circuit 58 is part of the fixed high frequency oscillator 57'. As is well known in the radio communication art, the outputs of the two high frequency oscillators are combined and introduced to a detecting stage, and the difference or beat frequency is filtered at the output of a beat frequency oscillator. I have shown a simple arrangement where the variable frequency is induced to coupling coil 56', and the fixed frequency is induced to coupling coil 58', said coils being connected in series with the primary 59' of transformer 59. The combined signals are introduced to a square-law detector stage 60, where the two original 70 75

5 quencies as well as their sum and difference frequencies are produced at its output. A filter 61, connected to the output of the detector 60 is designed to pass the low frequencies, corresponding to the difference or beat frequency of the two original high frequencies to the output 62 of the unit 54.

10 The lever 51 is preferably designed to operate over a relatively small arc, of the order of 20 to 30 degrees, in order that the amplitude of the excursion of plunger 44 may be sufficiently small so as to permit it to be designed to faithfully follow rapid picture shading variations. The motion of the plunger 44 is linked to the variable 15 condenser shaft 53, as already described, and the rotor plates 55 will correspondingly change the capacitance of the variable condenser to vary the frequency of the oscillator circuit 57. The frequency of the beat frequency oscillator output 20 is in this manner varied in accordance with the shading of the picture being transmitted.

25 When a black segment of the picture is scanned, no current is impressed on amplifier 6, and the plunger 44 is in its lowest position. The corresponding position of the rotor plates 55 may be made to correspond to a beat frequency output frequency, for example, of 4000 cycles or any other frequency depending upon the speed of transmission desired. When a white picture segment 30 passes the scanning beam and a strong signal flows into amplifier 6, the plunger is moved to its uppermost position and its excursion is made to correspond to an arc of movement of the lever 51 in the order of 20 to 30 degrees correspondingly rotating the shaft 53 and the rotor plates 55.

35 The electrical constants of the beat frequency oscillator are designed so that this relatively small arc of motion of the variable condenser 40 rotors 55 will change the beat frequency output from, for example, 4000 cycles to a lower frequency of, for example, 100 cycles. Since the frequency of excursion of the plunger 44 is relatively high, care must be exercised in design of 45 the mechanical system comprising the plunger 44 and its extension 49 and the co-acting lever 51 as well as the rotor plates 55 mounted on shaft 53. Provision must be made for a minimum of friction in the movement of the shaft 53, and 50 well oiled bearings or roller bearings should be used. The relative masses and compliances of the components of this moving mechanical system should be designed to avoid mechanical resonances in the range of frequency of mechanical vibration of this system by well known mechanical design methods.

55 The output 62 of the beat frequency oscillator 54 is coupled to the amplifier 32 by the transformer 28. The output 33 of the amplifier 32 60 may be transmitted over a line wire or caused to modulate a radio frequency carrier and radiated through an antenna system similar to the system described in connection with Figure 1 hereinabove. The beat frequency oscillator 54 is 65 designed to have a voltage output characteristic of constant amplitude with varying frequency. Thus, the modification embodied in Figure 2 translates the varying picture currents to signals of constant amplitude but frequency varying in 70 accordance with the shading of the picture being transmitted.

75 When a negative picture is being transmitted and a positive picture is to be reproduced at the receiving end, or when an actual picture is being transmitted and a negative of it is to be repro-

duced at the receiving end, the modifications according to Figure 2 may be designed to cause this effect in the following manner:

80 When the plunger 44 is attracted into the solenoid 43 as a picture segment is being scanned, the rotor plates 55 may be arranged to cause an increase in the beat frequency oscillator 54 output instead of decreasing the frequency as hereinabove described. Accordingly, when a black portion of the picture is being scanned, the 85 plunger 44 is not attracted up into the solenoid 43 and the low frequency, for example, 100 cycles is then produced by the beat frequency oscillator 54. By thus reversing the relative action of the 90 system, negatives of pictures are transmitted for 95 a positive received picture and vice versa.

100 A receiving system for recording the picture impulses as transmitted according to the modifications of Figures 1 and 2, is illustrated in Figure 3. I shall show the receiver in connection 105 with radio transmission of the facsimile signals although connections to line transmission may equally well be adapted by those skilled in the art. A receiving antenna 63 receives the radio 110 signal and introduces it to an ordinary radio 115 receiver 64. By means of switch 65 normally connecting to contact 66 so that the loud speaker 67 is connected to the radio set by leads 69, the 120 output of the receiver may be switched to the contact 68 so that facsimile signals which are 125 received and detected may be connected by leads 70 to the picture reproduction unit 71.

130 Unit 71 comprises an electro-magnet structure 72 with a winding 73 which is connected by leads 74 to a direct current source available in 135 any radio receiver. A circular core 75 forms a circular air gap 76 with the inside rim 77 of the soft iron magnet structure 72. This construction is similar to an ordinary electrodynamic unit 140 of the present type electrodynamic loud speaker. The movable coil 78 wound on form 79 is 145 interposed in the air gap 76. This coil form 79 is compliantly connected upon the core 75 by means of the resilient membrane 80 which is 150 mounted on the post 81 attached to the core 75. A suitable marker 82 is held in a retainer 83 which is connected to the suspended movable 155 coil system by the conical extension 84. The signal currents which are detected by the receiver 64 correspond to the signals of constant 160 amplitude and varying frequency which modulate the transmitting carrier wave. The output of the receiver 64 is connected to the movable 165 coil 78 by leads 70.

170 The detected facsimile signals produce alternating currents of constant amplitude in the movable coil 78 and cause it to vibrate in the air gap due to the magnetic reaction with the steady electro-magnetic flux in the air gap 76. The marker 82 is correspondingly caused to vibrate and produce marking impulses of varying 175 frequency. The marking energy of each impulse is substantially the same. As the reproducing unit 71 is moved along the paper 85, a series of 180 short marks or dots are made on the paper 85. The unit 71 is moved across the sheet of paper in 185 synchronism with the scanning of the picture being transmitted, to build up the received picture.

190 I have not shown any synchronizing means 70 because any one of many well known in the art may be employed. The reproducing unit 71 may traverse the paper sheet 85 in an arced path which is part of the circle in which the whole unit 75 rotates through. In a co-pending appli- 195

cation, I describe in detail a method for scanning and also reproducing a picture by imparting a rotary motion to the reproducing means similar to 71 by a plurality of such units as 71 being rotated so that as one unit completes marking, another unit starts marking at the beginning of the next line. However, I herein schematically indicate the circular motion imparted to unit 71 as follows: An arm 86 is bolted to the unit 71 and fastened to a beveled gear 87 attached to its shaft 88 which is rotatably supported by bracket 89. A coacting beveled gear 90, rotated by its shaft 91 imparts the continuous circular motion to the unit 71. In this application, I am not concerned with methods for synchronizing and details for the action of any particular system of scanning.

The system of transmission according to my invention as hereinabove described, transmits facsimile signals of constant amplitude. In systems utilizing amplitude modulation, the shading of the reproduced picture depends upon the relative magnitude of the received facsimile signal. The vagaries of radio transmission, particularly fading, impair the quality of the received picture because it distorts the relative signal strength received over a period of time. With my system of constant amplitude transmission, no such defect occurs because the shading of the reproduced picture depends upon the frequency of the marking impulses or dots. An ordinary automatic volume control circuit employed in a radio receiver is entirely satisfactory for reproducing clear and well defined pictures.

A further advantage of my facsimile system is that the received picture is built up with a plurality of discrete marking impulses or dots and is directly applicable for use in printing as in newspaper work. The marker 82 may well be a small chisel or etching tool for engraving the signal impulses directly on a zinc plate. The zinc plate is then used in connection with printing presses or other inking or reproducing mechanisms in a manner well known in the printing art. The "negative" of the desired picture should be translated on the zinc plate for "positive" printing of the picture.

My system may similarly be used with other types of marking or image recording means. The method I describe in my Reissue Patent No. 19,575 of electrolytic photographic recording on special chemically treated paper; or the use of a blunt marker 82 for impacting a carbon sheet or inked ribbon placed above an ordinary paper sheet; or the use of a marker 82 comprising a pencil point or inking stylus may be employed. The actual methods for scanning, recording or synchronizing do not form part of the present invention and any combination of well known methods may be used embodying the principles of the present invention.

A further modification for a transmitting system wherein facsimile signals of amplitude varying in accordance with the shading of the picture being transmitted are converted to corresponding constant amplitude signals of varying frequency is shown in Figure 2a. This is a modification using a beat frequency oscillator as in Figure 2 but providing for a variable frequency tank circuit wherein the capacitance to be varied is in the form of a flexible flat plate or disc spaced from a fixed plate.

Referring to Figure 2a, the light beam 5 of varying intensity impinges upon photo-electric cell 1 which produces corresponding signal varia-

tions at the input of the amplifier 6'. This amplifier 6' may be any suitable direct current amplifier with two ordinary output load 1' connecting to the movable coil 78 of the electrodynamic unit 71'. This unit is constructed similar to the unit 71 in Figure 3 and like numerals refer to corresponding elements. The beat frequency oscillator 54 circuit is schematically represented as in Figure 2, and like numbers refer to similar components.

A flexible metallic disk 201 is mounted with respect to the metallic casing 200 and insulated therefrom so that a capacitance exists between the casing 200 and the disk 201. The disk 201 is supported between the stretching rings 202 and 203 which are insulated from the casing 200 by means of insulation 204. Bolts 205 pass through the insulating bushing 207, and have nuts 206 for holding the disk stretching structure in position. The nuts 206 press against insulating washers 208. The condenser 213 accordingly comprises a stretched disk 201 spaced from a casing 200. Leads 209 and 210 connect this condenser 213 to the variable frequency tank circuit 56 of the beat frequency oscillator 54. A pin 211 mechanically connects the movable member 84 of the electrodynamic unit 71' to the stretched disk 201 at its center 212.

The varying light intensity resulting from the shading of the picture being scanned causes corresponding excursions of the movable coil 78 which transmits its motion to disk 201 with pin 211. The capacity of the condenser 213 is accordingly varied and correspondingly changes the frequency of the variable frequency oscillator 57 in a manner well known to those skilled in the art. The frequency at the output 62 of the beat frequency oscillator 54 is therefore varied in accordance with the shading of the picture signal being transmitted in a manner hereinabove explained in connection with Figure 2. The output 62 of beat frequency oscillator 54 is coupled to the amplifier 32 transformer 28 and may be transmitted over a land line 36 or modulate a radio frequency carrier for radio broadcasting as hereinabove described.

It is possible with the embodiment of Figure 2a to design a facsimile transmission system of greater speed as compared to that of Figure 2, since the moving elements of the translation from amplitude to frequency modulation means, namely the movable coil 78, element 84 pin 211 and flexible disk 201 are much smaller and lighter than the corresponding plunger 44, lever 51 and variable condenser 55. The design of the beat frequency oscillator 54 to utilize the comparatively small capacitance changes of the variable condenser 213 to produce corresponding output audio frequency variations from, for example, 4000 cycles to a hundred cycles according to the picture shading may be readily accomplished by those skilled in the communications art. The filter section of the beat frequency oscillator 54 is designed to pass through a band of signals corresponding to the predetermined signal range, for example, 4000 to 100 cycles, and no other frequency signals.

The principle which forms the basis of my invention may equally well be applied directly at the receiver. Transmitted amplitude modulated facsimile signals may be converted to marking impulses of constant intensity and varying frequency in such a receiver. A great advantage of such a system in conjunction with the

reproduction of amplitude modulated facsimile signals is that the energy for the marking impulses is locally generated and the received facsimile signals are used to produce the half-tone or shading effects in the reproduced picture by varying the frequency of the local marking impulses. The reproducer is a rugged, cheap and simple device and operates very efficiently with respect to the strength of the incoming signals. 5 A clear cut picture is reproduced by impulses of constant strength and the effects of fading in radio reception upon the appearance of the reproduced picture are greatly minimized. 10

Figure 4 is a schematic illustration of a commonly used amplitude modulated facsimile signal system. A spot of light from source 4 is concentrated upon the picture 2 mounted upon the drum 3 and is reflected along a beam 5 to the cell 1. An amplifier 6 is used to amplify the 15 photo-electric impulses in cell 1 and impress them upon a transmitting system similar to that used in Figure 1 through the coupling transformer 28. The amplitude modulated facsimile signals are further amplified at 32 and may be 20 alternatively transmitted by means of the land line 36 or used to modulate a radio frequency carrier wave transmitter. A light chopper 33 is used to interrupt the reflected beam 5 at a constant frequency so that ordinary amplifiers and 25 receivers may be used as is known by those skilled in the art. 30

The amplitude modulated facsimile signals are impressed upon the radio frequency carrier wave transmitted by the antenna 42 of the radio 35 transmission system schematically shown in Figure 4 and are received by the local antenna 63 of an ordinary radio receiver 64 as illustrated in Figure 5. The amplitude modulated facsimile signals transmitted by the system of Figure 4 are 40 polarized so that a darker picture element will produce an increased signal amplitude, and a brighter picture element, will cause a decreased signal amplitude. The output of the receiver 64 is switched from the speaker to the leads 70 by 45 means of switch 65 during facsimile reproduction. The detected facsimile signals, corresponding to the original modulating impulses at transformer 28 of Figure 4, are then passed through a suitable rectifier 100. For rugged, cheap, simple and 50 portable use, I prefer to employ a copper-oxide rectifier for further rectifying the facsimile signals and forming a substantially uni-directional energization of the solenoid 102a of the facsimile reproducer 103.

55 The solenoid 102 comprises the two coil sections 102a and 102b. An adjustable direct current is passed through the coil 102b to attract the plunger up into the solenoid 102. The polarity of the uni-directional current through coil 102a 60 is connected so that the magnetic flux produced by the coil 102a counteracts the steady magnetic attraction of coil 102b to permit the mechanically biased plunger 104 to be lowered. When a strong signal enters coil 102a, corresponding to a dark 65 picture segment, the plunger 104 assumes its lowest position with respect to the electro-magnet 115.

70 The reproducer 103 has a construction very similar to the corresponding electro-mechanical unit of the transmitter in Figure 1. A plunger 104 mechanically biased by spring 105 has a transverse pin 106 which abuts the edges 107 of insulation member 108. A projection 108' in member 108 limits the upward excursion of the 75 armature 112. A metallic extension 109 of the

plunger 104 carries a contact point 110 for contacting with the contact spring 111 attached to the armature 112. When no signal is received by solenoid 102a, corresponding to a white element of the picture being transmitted, the plunger 104 5 will be positioned up in solenoid 102 so that the armature 112 will stop vibrating due to the prevention of the contact between point 110 and spring 111. With signal current through solenoid 102, the contact point 110 moves down so 10 that it contacts contact spring 111. The armature 112 is attached to the metal spring 113 which is secured to the post 114.

15 The electro-magnet 115 is connected in series with a battery or direct current source 116, together with a rheostat 117 through the flexible connection 118 to the contact point 110 in series with the contact spring 111 and the armature 112 through the metal spring 113 and metallic post 114 back to the electro-magnet 115 by means 20 of connection 119. This local electromechanical circuit 120 operates at its predetermined highest frequency when maximum signal passes through the electro-magnet 102 and the plunger 104 is in its nearest position with respect to the electro-magnet 115. A retainer 121 holding a marker 122 is mounted at the end of the armature 112. A sheet 123 upon which the picture is to be reproduced is shown mounted upon a drum 124 which rotates in synchronism with the transmitting drum 3. The energy of the marking impulses is locally controlled by means of the rheostat 117 in the electro-mechanical circuit 120. 25

30 The electro-magnet 115 may very well be positioned at one side of the vibrating armature 112 instead of beneath it, to permit the armature 112 to be mounted nearer to the sheet being marked. I have accordingly shown a modification of the electromechanical system 120 in Figure 6 where the electro-magnet 115 is placed at a side of the 35 armature 112 and the poles 125 of this electro-magnet are extended underneath the armature 112. These poles 125 may be bent as illustrated so that the centers of the coils 126 are above the level of the poles 125. 40

45 Figure 7 is a sectional view through a preferred embodiment of the reproducing unit employing the principle schematically shown in Figure 6. A housing 127 encloses the reproducing unit 103 and is integrally formed with member 50 108. The member 108 has a recess enclosing the spring 104 and the transverse pin 106 similar to Figure 5. The solenoid 102 is mounted between the member 108 and the cover plate 128. The metal post 114 is set in the housing and supports 55 the vibrating armature. The poles 125 of the electro-magnet are shown set in the bottom of the structure. The coils 126 of the electro-magnet 115 are shown with their centers above the poles 125 so that a minimum distance is obtained 60 between the bottom 129 of the reproducing unit 123 and the vibrating armature 112. The retainer 121 and marker 122 project from the end of the armature 112. A sheet 130 is fed underneath the marking stylus 122 in any well known 65 manner. The sheet 130 may be mounted on a drum or fed continuously from a roll at a predetermined rate.

70 A hollow shaft 131 is affixed to the reproducing unit 103 as illustrated in Figure 7. The leads connecting to the solenoid 102, the contact point 110 and the electro-magnet 115 are passed through the hollow shaft 131 to form connections to the corresponding parts of the receiving circuit of Figure 5. The reproducing unit 103 is caused 75

to traverse over the surface of the paper 130 in synchronism with the scanning beam on the transmitted picture. Although as in the other embodiments, any preferred method for scanning and synchronizing may be employed, I have schematically illustrated a drive system for this reproducing unit 103 similar to that shown in connection with Figure 3. The shaft 131 is fastened to a shaft 132 on which is mounted the bevelled gear 133. A bracket 134 and sleeve 134' rotatably support the gear 133. A coacting bevelled gear 135 transmits the rotating drive power from shaft 136 to rotate the reproducing system 103 as explained in connection with the embodiment of Figure 3 hereinabove.

A further embodiment in the application of my invention is illustrated in the receiver of Figure 8. The facsimile signals from the receiver 64 which are further rectified by the copper oxide rectifier 100 is introduced to the solenoid 140 by means of the leads 101. The solenoid of this embodiment is used to transmit the effect of its attraction on the plunger 141 to the contact point 142 by means of a lever 143 which is supported 20 on an axis 144. The excursion of the contact point 142 is generally small for the vibrating electromechanical system. By suitable lever arrangement, the excursion of the plunger 141 may be made several times that of the contact point 142. The lever system 144 produces a mechanical advantage so that a positive control of the contact point 142 is had over the small excursions of contact 142 by relatively greater excursions of the plunger 141. It may be advantageous to 30 slightly curve the plunger 141 and its solenoid 140, as illustrated in Figure 8. Suitable mechanical stops 145 and 146 are arranged on either side of the vibrating lever 143. A spring 147 is used to mechanically bias the contact point 142 away 40 from the vibrating armature 112 shown in an end section view. The local electromechanical circuit 120 is similar to that of Figure 5, and like numerals refer to like parts. The relative masses and compliances of the components of this dynamic mechanical system are designed so that no mechanical resonances occur in the operating frequency range and the relative mechanical impedances of the co-acting mechanical parts are matched for maximum translation efficiency.

The embodiment of Figure 8 is shown constructed in such manner that when a "positive" of the original picture is received, a "negative" reproduction will result if black areas correspond to maximum transmitted facsimile signal 50 strength. When a dark area is being scanned, relatively large current will flow through the solenoid coil 140a and repel the plunger 141 to move the contact 142 away from the electromagnet 115 to decrease the frequency of vibration of the armature 112. A stylus connected at the end of this armature may be used to directly engrave a zinc plate to produce the required negatives for newspaper printing of the facsimile reproduction or other recording means may be 60 employed. By mechanical rearrangement, the lever system between the plunger 141 and the contact point 142 may be adapted for reproducing "positive" pictures when receiving "positive" facsimile signals.

Figures 9 and 10 are illustrations of further modifications which are particularly useful in facsimile transmission systems where black and white pictures are to be transmitted. My principle of utilizing local energization for the marking impulses is further simplified when the mark-

ing impulses are of only a constant frequency corresponding to black picture segments, and of zero frequency (no marking) corresponding to the white picture segments. In Figure 9 the receiving system shown is similar to that of Figures 5 and 8. The rectifier 100 converts the facsimile signals to uni-directional direct current which is conducted to the movable coil 150 of the electrodynamic reproducing unit 151 by leads 101. Another movable coil 152 is wound adjacent to coil 10 150 on a coil form 153. This coil 152 is connected to a local oscillating circuit 154 through the potentiometer 155. The remainder of this electrodynamic reproducing unit 151 is identical with the unit 11 of Figure 3 and corresponding parts have been labeled with the same number.

The energy for the marking impulses is locally supplied at a predetermined frequency by an alternating current generator 154. The leads 14 of the coil 153 connect to the direct current source 20 156 through a rheostat 157. The strength of the marking impulses is adjusted by either the position of the arm 158 on the potentiometer 155 or by the adjustment of the rheostat 157 or both. The alternating current locally produced in the movable coil 152 reacts with the steady magnetic field in the air gap 16 to vibrate the stylus 82 connected at the end of the movable coil system. When no current flows through signal coil 150, the marking impulses proceed 30 at a predetermined frequency for example, 4000 cycles, and produces a plurality of close dots on the paper which correspond to a black segment of the transmitted picture. When a white segment is being scanned, a facsimile signal 35 will result in a direct current flow through the rectifier 100 and the coil 150. The polarity of the direct current through the coil 150 is connected so that the action of the coil 150 is to decrease the strength of the downward or 40 marking impulse by a degree sufficient to avoid an actual mark upon the paper 85 and a corresponding white portion is obtained. The reproduced figure or facsimile message is composed of dark and white sections. The dark section 45 is a plurality of discrete dots or marks closely spaced. The facsimile signals are accordingly superimposed on a local marking circuit to act as an interrupter of the marking action. The translation efficiency is greatly increased by using 50 such a "negative action" facsimile reproduction means.

In Figure 10, I have illustrated a further modification of the "negative action" principle described in connection with Fig. 9. The radio receiver 64 and rectifier 100 is similar to that of Fig. 9 and the rectified facsimile signals are introduced to the winding 160 by leads 101. The winding 160 is wound on a soft iron core 161. Another winding 162 on the core 161 is connected to a direct source 163, through rheostat 164. The attraction for the armature 167 by the electromagnetic action of coil 162 on core 161 is adjustable by varying the biasing current by means of the rheostat 164. A local oscillator 165 passes alternating current of predetermined frequency through the winding 166 on the core 161.

The armature 167 is compliantly mounted on post 169 by spring 168. A spring 170 fixed at one end to the member 171, mechanically biases 70 the armature 167 away from the electromagnet core 161. A projection 171' in member 171 limits the excursion of the armature 167 upwards. A marker 173 is secured to the end of the armature 167 by the retainer 172. A sheet 174 is 75

wound on drum 175 similar in the other systems hereinabove described.

- The action of the local oscillator 165 is to cause a varying attraction on the armature 167 and 5 produce marking impulses of the marker 173 on the sheet 174, at the predetermined frequency. As the sheet moves with respect to the vibrating marking system, a succession of closely spaced marking dots or impulses are formed thereon. 10 The strength of the marking impulses is adjusted by varying the biasing direct current with rheostat 164. The rectified facsimile signal current flowing through the winding 161 is polarized so that it bucks the attraction of the armature due 15 to the local direct current in winding 162. When a facsimile signal corresponding to a white message area is received, it will buck the attractive force on the armature 167, and result in no marking imprint by the marker 173 on the sheet 174. 20 I have described in detail several embodiments and modifications of a system of facsimile transmission and reproduction which follow from the principles of my invention. Many variations may be made by those skilled in the art which 25 would come within the scope of my invention, and I do not intend to be limited except as set forth in the following claims.

I claim:

1. In a signaling system, means for translating a band of audio frequency currents of varying amplitude into a band of corresponding varying frequency and substantially constant amplitude audio frequency currents comprising a solenoid, an electromechanical vibrator having an armature and a variably positioned contact member for changing the frequency of vibration of said armature, means for mechanically regulating the position of said contact member by said solenoid, said solenoid being electrically connected to said 30 varying amplitude currents, a transformer and a source of current, said contact member and said armature being circuitally connected with a winding of said transformer and said source whereby alternating current of frequency varying 35 in accordance with the frequency of vibration of said armature is induced to the output of said transformer.

2. In a signaling system, means for translating a band of audio frequency currents of varying 50 amplitude into a band of corresponding varying frequency, and substantially constant amplitude audio frequency currents comprising a solenoid, said solenoid being electrically connected to said varying amplitude currents, an oscillator circuit 55 including a variable condenser for varying the frequency of the alternating current output of said oscillator, a second oscillator circuit for generating alternating current of substantially fixed frequency, means for beating the alternating current 60 outputs of said first and second oscillators, filter circuit means for passing through the audio frequency currents from said beat frequency means and means including mechanical connections controlled by said solenoid for varying the capacitance of said variable condenser in accordance with said varying amplitude currents.

3. In a signaling system, means for translating a band of audio frequency currents of varying amplitude into a band of corresponding varying 70 frequency and substantially constant amplitude audio frequency currents comprising an electrodynamic unit having a coil movable in a substantially uniform magnetic field, said movable coil being electrically connected to said varying amplitude currents and an oscillator circuit includ-

ing a variable condenser for varying the frequency of the alternating current output of said oscillator; a second oscillator circuit for generating alternating current of substantially fixed frequency, means for beating the alternating current outputs of said first and second oscillators, filter circuits means for passing through the audio frequency currents from said beat frequency means and means including mechanical connections controlled by said movable coil for varying 10 the capacitance of said variable condenser in accordance with said varying amplitude currents.

4. In a signaling system means for translating a band of audio frequency currents of varying amplitude into a band of corresponding varying frequency and substantially constant amplitude audio frequency currents comprising electromechanical means responsive to said varying amplitude currents, a first oscillator circuit including a variable condenser for varying the frequency 20 of the alternating current output of said oscillator, means including mechanical connections controlled by said electro-magnetic means for varying the capacitance of said variable condenser, a second oscillator circuit for generating 25 an alternating current of substantially fixed frequency, and means including circuit connections for beating the alternating current outputs of said first and second oscillators to produce said varying audio frequency currents.

5. In a signaling system means for translating a band of audio frequency currents of varying amplitude into a band of corresponding varying frequency and substantially constant amplitude audio frequency currents comprising a solenoid 30 electrically connected to said varying amplitude currents, a plunger controlled by said solenoid, a first oscillator circuit including a variable condenser for varying the frequency of the alternating current output of said oscillator, means including mechanical connections controlled by said plunger for varying the capacitance of said variable condenser, a second oscillator circuit for generating an alternating current of substantially 35 fixed frequency, and means including circuit connections for beating the alternating current outputs of said first and second oscillators to produce said varying audio frequency currents.

6. In a signaling system means for translating a band of audio frequency currents of varying 40 amplitude into a band of corresponding varying frequency and substantially constant amplitude audio frequency currents comprising an electrodynamic unit having a coil movable in a substantially uniform magnetic field, said movable coil 45 being electrically connected to said varying amplitude currents, a first oscillator circuit including a variable condenser for varying the frequency of the alternating current output of said oscillator, means including mechanical connections controlled by said movable coil for varying the capacitance of said variable condenser, a second oscillator circuit for generating an alternating current of substantially fixed frequency, and means including circuit connections for beating the alternating current outputs of said first and second oscillators to produce said varying audio frequency currents.

7. In a signaling system means for translating a band of audio frequency currents of varying 50 amplitude into a band of corresponding varying frequency and substantially constant amplitude audio frequency currents, comprising a solenoid 55 electrically connected to said varying amplitude currents.

currents, a plunger controlled by said solenoid, a first oscillator circuit including a variable condenser for varying the frequency of the alternating current output of said oscillator, said variable condenser having a rotor section, said rotor section being mechanically controlled by said plunger for varying the capacitance of said condenser, a second oscillator circuit for generating an alternating current of substantially fixed frequency, and means including circuit connections for beating the alternating current outputs of said first and second oscillators to produce said varying 5 audio frequency currents.

WILLIAM G. H. FINCH.
